LERoy J. BUTTOLPH, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

MERCURY-VAPOR LAMP AND RECTIFIER-STARTING APPARATUS.

Application filed November 29, 1924. Serial No. 752,995.

My present invention relates to method and apparatus for the starting and operation of a mercury arc lamp on an alternating current circuit and of a rectifier used for rectifying the current from such circuit. It relates particularly to apparatus for use on alternating current and including a rectifier and a vapor lamp in which an arc is drawn in the lamp by the tilting thereof and in which the rectifier is started by an inductive kick produced by current passing upon the short circuiting of the electrodes of the lamp when it is tilted, the lamp being returned into operating position upon the establishment of contact between the electrodes thereof by the flowing mercury therein.

Heretofore in starting and operating apparatus for vapor arc lamps on alternating current circuits there has been employed an auxiliary starting electrode for the rectifier and a magnetic cut out therefor for short circuiting it on the starting of the rectifier and an auxiliary starting load, in multiple with the main load. But in the apparatus of my invention these parts have been eliminated.

The figure is a diagrammatic representation of a vapor arc lamp and a rectifier therefor connected to a source of alternating current.

In the drawing the alternating current supply main 1 and 2 feed the auto-transformer 3 which connects thereto at the intermediate points 4 and 5. The lead 7 from substantially the midpoint of the auto-transformer 3 leads to the cathode of a vapor arc lamp 10 and other apparatus as hereinafter described. The leads 6 and 8 from the outer terminals of said transformer 3 connect with the rectifier 9 at the anodes 16 and 17 thereof, respectively. The mercury vapor arc lamp 10 connects with said lead 7 at its cathode 19 and with the cathode 18 of rectifier 9 by a connector 23 from the anode 20 of lamp 10, through the inductance 14, and to the cathode terminal lead 24 of said rectifier 9. The resistance 11 in series between transformer 3 and lamp 10 in said lead 7 serves as a stabilizer for the lamp and rectifier current. Said inductance 14 serves also as a stabilizer for the lamp and rectifier current and also for the purpose of producing an inductive kick for the starting of the rectifier as hereinafter fully described. Connection

is made from said lead 6 by way of lead 21, resistance 12, lead 22, shifter 13, to the anode terminal 24 of said rectifier 9. The lead 25 connects the starting band 15 of rectifier 9 to said lead 22. Said inductance 14 in addition to the functions noted above also serves to operate said shifter 13 in the manner well known in the art.

In the use and operation of the apparatus of my invention to start the rectifier and lamp said lamp 10 is tilted from the vertical position to a horizontal position and returned to the vertical operating position as shown in the drawings. During the time that the lamp is in the horizontal position the cathode mercury 19 thereof flows and contacts with said anode 20 thereby establishing a current path from the midpoint of transformer 3 through said lead 7 and the resistance 11 connected in series therein, through the lamp 10, lead 23, inductance 14, shifter 13 (which is in the closed circuit position when current is not flowing through said inductance 14), through lead 22, resistance 12, lead 21, and through lead 6 to an outer terminal of said transformer 3. Upon flow of current through said inductance 14 said shifter 13 is actuated thereby for the opening thereof whereupon said inductance 14 having the flow of current therethrough suddenly interrupted has high re-active kick induced therein which is discharged statically from the starting band 15 whence the induced current flows through lead 25 and resistance 12, lead 21, anode 16 and the mercury vapor in-said rectifier 9 whereupon a spark is struck between said anode 16 and the mercury 18 of the rectifier. Upon the establishment of said arc between anode 16 and cathode 18 said cathode 18 is sufficiently vaporized to produce a conducting path both between anode 16 and cathode 18 and between anode 17 and cathode 18 whereby the arc between anode 16 and cathode 18 is continued and another arc between anode 17 and cathode 18 is established. Current will now flow from both the outer end terminals of transformer 3 alternating according to the cycles of the alternating current supply through rectifier 9 by way of its cathode 18 through inductance 14, lead 23, lamp 10, and lead 7, to the midpoint of transformer 3 in the manner well known in the rectifier art. Upon such establishment of current flow in the rectifier the lamp 10 is returned to its

normal vertical operating position whereupon an arc is struck between its terminals which are will be maintained and continued by the flow of the rectified current therethrough.

5. I claim—

1. In a mercury vapor arc lamp circuit, in combination, alternating current feed mains, a transformer connected thereto, a two anode mercury vapor arc rectifier connected 10 by said anodes to said transformer, a connection from said transformer to the cathode of said rectifier having in series therein a resistance, a mercury vapor arc lamp and an inductance, a switch connected on one side 15 between said inductance and said cathode and on the other side to an electrode on the outside wall of said rectifier adjacent said cathode, a resistance connected on one side to a point between said electrode and said 20 switch and on the other side to said transformer.

2. In a mercury vapor arc lamp circuit, in combination, alternating current feed mains, a transformer connected thereto, a two 25 anode mercury vapor arc rectifier connected by said anodes to said transformer, a connection from said transformer to the cathode of said rectifier having in series therein a resistance, a mercury vapor arc lamp and 30 an inductance, a switch connected on one side between said inductance and said cathode and on the other side to an electrode on the outside wall of said rectifier adjacent said cathode, a resistance connected on one side to 35 a point between said electrode and said switch and on the other side to a point between one of the anodes and its connection to said transformer.

3. In automatic starting apparatus for 40 alternating current mercury vapor arc lamps, in combination, a source of alternating current supply, a two anode rectifier therefor, a transformer connected between said supply and said rectifier, a connection 45 from said transformer to a mercury vapor arc lamp and from said lamp to the cathode of said rectifier, a connection from one of said anodes to the rectifier cathode with a switch therein, an electrode outside said rectifier adjacent said cathode connected to a point between said switch and the anode 50 connected thereto, and singular inductive means for providing a high inductive kick across the terminals of said rectifier, for maintaining the rectifier current, and for stabilizing the mercury vapor arc lamp current.

4. An automatic starting apparatus for 55 alternating current mercury vapor arc lamps, in combination, a source of alternating current supply, a two anode rectifier therefor, a transformer connected between said supply and said rectifier, a connection from said transformer to a mercury vapor arc lamp and from said lamp to the cathode

of said rectifier, a connection from one of said anodes to the rectifier cathode with a switch therein, an electrode outside said rectifier adjacent said cathode connected to a point between said switch and the anode 70 connected thereto, a resistance in series with said lamp, and singular inductive means for providing a high inductive kick across the terminals of said rectifier, for maintaining the rectifier current, and for stabilizing the 75 mercury vapor arc lamp current.

5. An automatic starting apparatus for alternating current mercury vapor arc lamps, in combination, a source of alternating current supply, a two anode rectifier 80 therefor, a transformer connected between said supply and said rectifier, a connection from said transformer to a mercury vapor arc lamp and from said lamp to the cathode of said rectifier, a connection from one of said anodes to the rectifier cathode with a switch therein, an electrode outside said rectifier adjacent said cathode connected to a point between said switch and the anode 85 connected thereto, a resistance between said electrode and said anode, a resistance in series with said lamp on the cathode side, and singular inductive means for providing a high inductive kick across the terminals of said rectifier, for maintaining the rectifier current, and for stabilizing the mercury vapor 90 arc lamp current.

6. In mercury vapor arc lamp apparatus, in combination, a mercury vapor arc lamp, a source of alternating current supply, an 100 auto-transformer connected at intermediate points to said supply, a mercury vapor rectifier having two anodes, a cathode, and an electrode outside its envelope adjacent said cathode, a connection from the midpoint of said transformer through a resistance to the cathode of said mercury vapor arc lamp, a connection from the anode of said lamp and through an inductance to the cathode of said rectifier, connections from the extremities of said transformer respectively to said rectifier anodes, a connection from one of said anodes through a resistance to said outside electrode and a connection from said outside electrode through a switch to the rectifier 105 cathode.

7. The method of starting a mercury vapor arc lamp and a rectifier therefor having an inductance in series therewith which consists in simultaneously tilting said lamp to 110 establish connection between the electrodes thereof through the mercury thereof and short circuiting said rectifier through external connections, and then simultaneously restoring said mercury vapor lamp to its normal position and breaking said short circuit of said rectifier, whereby a high inductive kick is produced through said rectifier to establish an arc between the electrodes thereof.

8. In a mercury vapor arc lamp circuit, 115

- in combination, alternating current feed mains, a transformer connected thereto, a two anode mercury vapor arc rectifier connected by said anodes to said transformer, a connection from said transformer to the cathode of said rectifier having in series therein a resistance, a mercury vapor arc lamp adapted to be tilted to connect its anode and cathode through the mercury thereof and an inductance, a switch connected on one side between said inductance and said cathode and on the other side to an electrode on the outside wall of said rectifier adjacent said cathode, a resistance connected on one side to a point between said electrode and said switch and on the other side to said transformer. 15
